UNITED STATES PATENT OFFICE.

CARL HOLLWEG, OF BARMEN, PRUSSIA, GERMANY.

POCKET-KNIFE.

SPECIFICATION forming part of Letters Patent No. 364,414, dated June 7, 1887.

Application filed January 20, 1887. Serial No. 224,886. (No model.)

To all whom it may concern:

Be it known that I, CARL HOLLWEG, of Barmen, Rhenish Prussia, Germany, have invented a new and Improved Knife, of which the following is a full, clear, and exact description.

The object of my invention is to provide a new and improved knife with movable blades in which all springs are dispensed with, and in which each blade is held in a locked position when opened or closed, and the blade is opened without being touched by the operator.

The invention consists of various parts and details and combinations of the same, as will be fully described hereinafter, and then pointed out in the claims.

Reference is to be had to the accompanying drawings, forming part of this specification, in which similar letters of reference indicate corresponding parts in all the figures.

Figure 1 is a perspective view of my improvement with the blades open. Fig. 2 is a similar view of the same with the blades closed. Fig. 3 is a sectional plan view of the same on the line *xx* of Fig. 2. Fig. 4 is a side elevation of the same with parts removed. Fig. 5 is an elevation of the back locking-plate. Fig. 6 is a perspective view of one of the knife-blades; and Figs. 7 to 13 are detail views of parts of the knife, hereinafter more fully described.

The knife casing or handle consists of two side pieces or plates, A, on each of which can be secured an ordinary handle, B. The two side pieces are fastened together by rivets R, on which turn the knife-blades, and by a back plate, C, (see Fig. 5,) provided with the lugs *h*, which fit in corresponding recesses, *p*, formed in the said side plates, A.

Each of the knife-blades K is provided with the usual aperture, *a*, through which passes the rivet R, and with a second square aperture, *b*, which corresponds with the square aperture *b'* formed in the turning-plate E, (see Fig. 7,) adapted to turn on the said rivet R. In the apertures *b* and *b'* fit the trunnions of the carrying-pin F, (see Figs. 11 and 3,) adapted to slide in the semicircular recess *f*, formed in the side plates, A.

It will be seen that when the plate E is turned the knife-blade K is also turned with

it by being connected by the said carrier-pin F with the said plate E. The turning-plate E is also provided with recesses *m m*, into which fit the lugs or trunnions *i i*, formed on the handle D, (see Fig. 8,) so that the latter can be turned at right angles to or in line with the said plate E. The parts D and E are held on the plate A, by the washer G, which fits over the central part of the plate E and over the trunnions *i i* of the handle D. The rivet R holds the washer G in place. (See Fig. 3.)

The handle D is provided in its rim with two recesses, *r r*, placed opposite each other, and into which fits a corresponding lug, *n*, formed on the locking-plate H, secured to the side plate, A, as shown in Figs. 1, 2, and 4. If two knife blades K are fulcrumed on one rivet R, as shown in Fig. 3 and the lower parts of Figs. 1 and 2, then I place a partition-plate, L, (shown in Fig. 13,) between the said knife-blades K, as shown in Fig. 3; but if only one knife-blade K is fulcrumed on the rivet R, as shown in the upper part of Figs. 1 and 2, then I use a partition-plate, L, (see Fig. 13,) on each side of the knife-blade K. This partition-plate L is provided with the semicircular slot *f'*, corresponding to the slot *f* in the side plate, A. In the latter case I need but one handle D on one side of the knife, and the other side of the knife is provided with a semicircular plate, J, without a handle, as shown in Fig. 12.

The operation is as follows: When the knife is in a closed position, as shown in Fig. 2, and the operator desires to open one of the knife-blades, he moves the respective handle D into a right-angular position to the plate E, and by inserting his finger-nail under the inclined edge *d* of the handle D presses the latter upward. This upward movement throws the notch *r* out of contact with the lug *n* on the locking-plate H, and the operator then turns the handle D, whereby the plate E turns with the handle D and the respective knife-blade K turns with the plate E on account of its connection with the latter by the carrier-pin F. As soon as the respective knife-blade K is fully opened, as shown in Fig. 1, then the operator presses the handle D flat upon the plate A, whereby the other notch, *r*, engages the lug *n* on the locking-plate H, and the knife-blade K is

thus held locked in the open position, as the handle D and the plate E are prevented from turning.

It will be seen that the knife-blades can all be independently opened or closed and held locked in either position without compelling the operator to touch the knife-blades. It will also be seen that no springs of any description are used in the construction of my knife.

10 The improvement can be used on pocket-knives or larger knives, and it can also be adapted to corkscrew-blades, &c.

Having thus fully described my invention, I claim as new and desire to secure by Letters 15 Patent—

1. The combination, with the handle, the side plates of which are immovable with respect to each other, of a blade pivoted within the handle and provided with an outer independent handle for throwing it into or out of the knife-handle, substantially as set forth.

2. The combination, with the handle, the side plates of which are immovable with respect to each other, and a locking-lug on the 25 outer side of the handle, of a blade pivoted within the handle and provided with an outer independent handle adapted to engage the said locking-lug, and thereby lock the blade when thrown, substantially as set forth.

3. In a knife, the combination, with a knife-blade, of a carrier-pin connected with the said blade, a turning-plate connected with the said carrier-pin, and a handle pivoted on the said turning-plate, substantially as shown and de- 30 scribed.

4. In a knife, the combination, with a knife-blade, of a carrier-pin connected with the said knife-blade, a turning-plate connected with the said carrier-pin, a handle pivoted on the said turning-plate, and a locking-plate for locking the said handle in position, substantially as shown and described.

5. In a knife, the combination, with a knife-casing and the rivet on which turns the knife-blade, of a knife-blade having a square aperture at one side of its fulerum, a carrier-pin fitting into the square aperture of the knife-blade, a plate turning on the said rivet and connected with the said carrier-pin, and a handle hinged on the said turning-plate, substantially as shown and described.

6. In a knife, the combination, with a knife-casing and the rivet on which turns the knife-blade, of a knife-blade having a square aperture on one side of its fulerum, a carrier-pin fitting into the said square aperture of the knife-blade, a plate turning on the said rivet and connected with the said carrier-pin, a handle hinged on the said turning-plate, and a locking-plate secured to the said knife-casing and serving to hold the said handle in a locked position, substantially as shown and described.

7. In a knife, the combination, with the knife-casing and the rivet on which turns the

knife-blade, of a knife-blade having a square aperture on one side of its fulerum, a carrier-pin fitting into the said square aperture of the knife-blade, a plate turning on the said rivet and connected with the said carrier-pin, a handle hinged on the said turning-plate, and a locking-plate secured to the said knife-casing and serving to hold the said handle in a locked position, and a washer for holding the said handle on the said turning-plate, substantially as shown and described.

8. In a knife, the side plates, A, having the semicircular slot f, the rivet R, and the back, in combination with the knife-blade K, turning on the said rivet R, and having a square aperture, b, the carrier-pin F, sliding in the 80 said semicircular recess f of the said plate A, one end of which pin F fits into the said square aperture b of the knife-blade, and an outer handle for moving the said carrier-pin in the said semicircular slot f, substantially as set forth.

9. In a knife, the side plates, A, having the semicircular slot f and the recesses p, the rivet R, and the back plates, C, having the lugs h, fitting into the said recesses p of the side 90 plates, A, in combination with the knife-blade K, turning on the said rivet R, and having a square aperture, b, the carrier-pin F, sliding in the said semicircular recess f of the side plate, A, one end of which pin F fits into the said square aperture b of the knife-blade, the turning-plate E, fulcrumed on the said rivet R, and provided with the square aperture b', into 95 which fits the other end of the carrier-pin F, the handle D, hinged on the said turning-plate 100 E, the locking-plate H, provided with the lug n, on which fit the notches r in the said handle D, and the washer G, holding the lugs i on the handle D in the recesses m of the turning-plate E, substantially as shown and de- 105 scribed.

10. In a knife, a knife-casing provided with the side plates, A, having the semicircular recesses f, the back plate, the rivet or blade-pivot, and the knife-blade K, turning in the said casing on the said rivet or pivot, and provided with a square aperture, b, in combination with the carrier-pin F, sliding in the said semicircular recess f of the side plate, one end of which pin F fits into the said square 115 aperture b of the knife-blade, the turning-plate E, provided with the square aperture b', into which fits the other end of the said carrier-pin, F, the handle D, hinged on the said turning-plate E, and the locking-plate H, having the lug n, on which fits one of the notches r of the said handle D, substantially as shown and described.
